No. 607,925.

Patented July 26, 1898.

C. P. GANO.

PUMPING JACK.

(Application filed Jan. 20, 1898.)

(No Model.)

UNITED STATES PATENT OFFICE.

CHARLES P. GANO, OF BOWLING GREEN, OHIO.

PUMPING-JACK.

SPECIFICATION forming part of Letters Patent No. 607,925, dated July 26, 1898.

Application filed January 20, 1898. Serial No. 667,300. (No model.)

To all whom it may concern:

Be it known that I, CHARLES P. GANO, a citizen of the United States, residing at Bow-
ling Green, in the county of Wood and State
5 of Ohio, have invented a new and useful
Pumping-Jack, of which the following is a
specification.

My invention relates to oil-well pumping-
jacks, and has for its object to provide simple
10 and efficient means for taking up or letting
out the connection between the surface rods
and the pumping-lever or V, to vary the in-
terval between the pump-valves to secure the
desired efficiency of stroke without varying
15 the length of the surface rods or otherwise
materially interfering with the operation of
the mechanism.

A further object of the invention is to pro-
vide an improved construction of pumping-
20 lever or V and means for mounting and brac-
ing the same.

Further objects and advantages of this in-
vention will appear in the following descrip-
25 tion, and the novel features thereof will be
particularly pointed out in the appended
claims.

In the drawings, Figure 1 is a view of a
pumping mechanism constructed in accord-
ance with my invention. Fig. 2 is a detail
30 view of the rocker and polish-rod clamp. Fig.
3 is a similar view of the angle of the pump-
ing-lever or V and the bearings in which the
trunnions of the same are mounted. Fig. 4 is
35 a similar view of the casing-head clamp. Fig.
5 is a similar view of the connections between
the surface rod and the pumping-lever or V.
Fig. 6 is a detail plan view of the polish-rod
clamp.

Similar numerals of reference indicate cor-
40 responding parts in all the figures of the draw-
ings.

Connected with the polish or sucker rod 1
is a clamp 2, consisting of a block 3, having
a vertical seat 4 of a depth greater than the
45 diameter of the polish-rod, and a removable
cap-plate 5 for arrangement parallel with the
face of the block 3 to cover the mouth of the
seat 4 therein and provided with a projection
50 6, having a V-shaped face for contact with the
polish-rod. This cap-plate is fitted upon bolts
7, projecting from the block 3 and is adapted
to be held in place at the desired adjustment by

means of nuts 8 or their equivalents threaded
upon said bolts. The body portion or block
3 of the clamp is provided with alined lateral
55 trunnions 9, which are connected by means of
links 10 with similar trunnions 11 on the sides
of a segmental-faced rocker 12, carried by the
upper approximately horizontal arm 13 of the
pumping-lever or V, said arm preferably con-
60 sisting of parallel bars spaced apart at a short
interval and bolted or riveted at one end to
the rocker and at the other end to one arm of
a fulcrum-angle 14. This angle is the means
of connection between said bars forming the
65 arm 13 and similar bars forming an approxi-
mately vertical arm 15, said arms being con-
nected by a brace 16, which occupies the po-
sition of a hypotenuse and is connected at
one end to the bars of the arm 15 by a union
70 17. The angle 14 is provided with lateral
trunnions 18, mounted in bearings 19, having
removable caps 20, and said bearings 19 are
supported by stationary braces 21, which are
stepped at their lower ends upon a stationary
75 object, such as the casing-head 22. As a means
of connection between the feet of the braces
21 and the casing-head I employ a clamp 23,
consisting of a looped rod 24, having its looped
end hooked, as shown at 25, to engage the
80 casing-head at one side and having its arms,
which extend transversely across the casing-
head upon opposite sides of the well-tubing,
fitted in sockets 26 on a claw 27, which en-
gages the casing-head at the opposite side
85 from the hook 25. Nuts 28 are threaded upon
the extremities of the arms to tighten the
clamp upon the casing-head. Also the claw 27
is provided with eyes 29, to which are bolted
the lower extremities of the members of the
90 brace 21. A brace-rod 30 extends downwardly
and rearwardly from each bearing 19.

Fitted upon the lower extremities of the
members of the arm 15 are castings 31, be-
tween which extends a pin 32 for engagement
95 by the hooked extremity 33 of a holding-rod
34, which is mounted for pivotal movement
in a vertical plane upon a cross-bar 35 on the
claw 27. Also mounted for vertical adjust-
ment upon the members of the arm 15 are
100 bearing-clamps 36, having alined bearings 37
to receive the trunnions 37^a of a ratchet-guide
38, in which operates a ratchet-bar 39. Ob-
viously the trunnions of the guide may be

- engaged with either pair of bearings 37, of which two or more, at different distances from the fulcrum of the pumping-lever or V , are provided in the clamps 36. This ratchet-bar 5 guide carries a vertically-movable dog 40 for engagement with the teeth of the ratchet-bar, and connected with the dog is a trip-lever 41, pivotally mounted upon the guide and adapted when elevated at its free end to disengage 10 the dog from the ratchet-bar. A detent 42 is also preferably employed in connection with the trip-lever to maintain the latter in such a position as to hold the dog out of engagement with the ratchet-bar.
- 15 From the above description it will be seen that the connection between the several parts of the jack embodying my invention are simple and are such as to readily facilitate the assembling and disconnecting of the members, and it is obvious that in case the surface rod (indicated at 43) becomes stretched or for any other reason the polish-rod is allowed to drop so as to bring the valves of the pump too close together for efficient operation the slack may be taken up and the operating-valve of the pump returned to its proper position with relation to the other parts of the mechanism without checking the operation of the surface rod by raising the free 25 end of the holding-rod 34 and engaging its hook 33 with the pin 32, and thereby allowing the ratchet-bar to be drawn back independently of the pumping-lever or V to cause the engagement of the dog 40 with a different tooth of the ratchet-bar. If it is desired to cause the dog to engage with a tooth removed only two or three spaces from that with which it is engaged at the time, the dog may be held elevated out of engagement with the ratchet- 30 bar until the ratchet-bar has been advanced on the succeeding stroke to bring the desired tooth thereof into the path of the dog. Obviously this operation of holding the dog temporarily out of engagement with the ratchet-bar may be accomplished manually by grasping 40 the trip-lever 41.
- 45 A further advantage of the above-described adjustable connection between the surface rod and the pumping-lever or V resides in the fact that in case it is desired to "bump" the pumping mechanism to dislodge sticking valves the dog may be tripped manually at the end of the forward stroke to release the pumping-lever and thus allow the polish-rod 50 to drop the full length of the stroke unimpeded by the operating mechanism. In the same way various other advantages, which will be apparent to those skilled in the art, will result from a construction which allows 55 the pumping-lever or V to be disconnected temporarily from the surface rod, and from the fact that the operator is enabled to cause the reengagement or connection of said parts at any desired point in the stroke of the operating mechanism. Also by mounting the ratchet-bar guide at different distances from the fulcrum of the pumping-lever or V the

length of the stroke may be varied to suit the function to be performed by the pump and the peculiar conditions under which the 70 pumping operation is progressing.

Various changes in the form, proportion, and the minor details of construction may be resorted to without departing from the spirit or sacrificing any of the advantages of this 75 invention.

Having described my invention, what I claim is—

1. In a pumping-jack, the combination of a pumping-lever or V having lateral trunnions at its fulcrum-point, forwardly and downwardly extending brace-rods provided with bearings in which said trunnions are mounted, a casing-head clamp having a looped rod provided with an intermediate hook to 80 engage a casing-head at one side, and a claw adjustably connected with the arms of said loop and connected with the contiguous lower extremities of said brace-rods, substantially as specified.

2. In a pumping-jack, the combination with a pumping-lever or V and a reciprocatory operating-rod, of a pawl-and-ratchet-bar connection between said lever and rod, substantially as specified.

3. In a pumping-jack, the combination with a pumping-lever or V , of a reciprocatory ratchet-bar, a guide carried by the pumping-lever, and a pawl mounted upon the guide for engagement with the teeth of the ratchet-bar, substantially as specified.

4. In a pumping-jack, the combination with a pumping-lever or V , of a reciprocatory ratchet-bar, a ratchet-bar guide mounted upon one arm of the pumping-lever or V for 105 adjustment parallel therewith, and a pawl carried by the guide for engagement with the teeth of the ratchet-bar, substantially as specified.

5. In a pumping-jack, the combination with a pumping-lever or V , of a reciprocatory ratchet-bar, a plurality of bearings carried by an arm of said lever or V , a ratchet-bar guide having trunnions mounted in one of said bearings, and a pawl carried by the guide 115 for engagement with the teeth of the ratchet-bar, substantially as specified.

6. In a pumping-jack, the combination with a pumping-lever or V , of clamps carried by one arm of the pumping-lever and having a 120 plurality of bearings spaced at different intervals from the fulcrum of the lever or V , a reciprocatory ratchet-bar, a ratchet-bar guide having trunnions mounted in aligned bearings of said clamps, and a pawl carried by the 125 guide for engagement with the teeth of the ratchet-bar, substantially as specified.

7. In a pumping-jack, the combination with a pumping-lever or V , of a reciprocatory ratchet-bar, a pawl carried by the pumping-lever or V for engagement with the teeth of the ratchet-bar, and locking devices for securing the pumping-lever or V in a fixed position, substantially as specified.

8. In a pumping-jack, the combination with a pumping-lever or V , of a reciprocatory ratchet-bar, a pawl carried by the pumping-lever or V for engagement with the teeth of the ratchet-bar, and a movable holding-rod for engagement with the pumping-lever or V to maintain it temporarily in a fixed position, substantially as specified.

9. In a pumping-jack, the combination with a pumping-lever or V , of a reciprocatory ratchet-bar, a pawl carried by the pumping-lever or V for engagement with the teeth of the ratchet-bar, a movable holding-rod for engagement with the pumping-lever or V to maintain it temporarily in a fixed position, and a trip-lever connected with said pawl to provide for the manual disengagement of the pawl from the ratchet-bar, substantially as specified.

10. In a pumping-jack, the combination with a pumping-lever or V , of a reciprocatory ratchet-bar, a pawl carried by the pumping-lever or V for engagement with the teeth of the ratchet-bar, a pin carried by an arm of the lever or V , a casing-head clamp, and a holding-rod pivotally mounted upon the casing-head clamp and having a hooked extremity for engagement with said pin to maintain the pumping-lever or V temporarily in a fixed position, substantially as specified.

In testimony that I claim the foregoing as my own I have hereto affixed my signature in the presence of two witnesses.

CHARLES P. GANO.
